COMBINED HIGHWAY FLARE AND STAND THEREFOR

J. D. Moncrief, 3139 Woodmark Court,
Sacramento, Calif. 95821

Filed June 17, 1974, Ser. No. 479,989

Term of patent 14 years

Int. Cl. D10—06

U.S. Cl. D10—114

FIG. 1 is a top plan view of a combined highway flare and stand therefor, showing my new design;

FIG. 2 is an elevational view of one side, the opposite side being substantially in mirror symmetry;

FIG. 3 is an end view of the right-hand end of FIG. 2;

FIG. 4 is an end view of the left-hand end of FIG. 2;

FIG. 5 is a bottom plan view;

FIG. 6 is a fragmentary median, longitudinal, sectional view, to an enlarged scale, of the right-hand end of FIG. 5; and

FIG. 7 is an isometric perspective view of the flare and stand in operative position, with the flare reversed end for end relative to the igniter sleeve and protective cap after ignition and with the two half-loops of wire unhooked from the flare body and the two wire legs bent to support the flare at an elevated angle.

I claim:

The ornamental design for a combined highway flare and stand therefor, as shown and described.
